UNITED STATES PATENT OFFICE.

BENJAMIN BUNDY, OF SABINA, OHIO.

PERMUTATION-LOCK.

SPECIFICATION forming part of Letters Patent No. 531,902, dated January 1, 1895.

Application filed April 27, 1894. Serial No. 509,253. (No model.)

To all whom it may concern:

Be it known that I, BENJAMIN BUNDY, a citizen of the United States, residing at Sabina, in the county of Clinton and State of Ohio, have invented certain new and useful Improvements in Combination-Locks; and I do hereby declare the following to be a full, clear, and exact description of the invention, such as will enable others skilled in the art to 10 which it appertains to make and use the same.

My invention relates to improvements in combination locks; and the object thereof is to provide a simple, effective and durable means for holding the bolt or locking device 15 in a fixed position; and to provide certain registering devices or combinations which when arranged in some predetermined position will release a slide or plunger or other movable bolt-engaging device, but when not 20 in this position will prevent movement of the same, thereby rigidly holding the bolt of the lock.

Another object is to provide means for arranging the registering devices or combinations in any predetermined position.

A further object of my invention is to provide a bolt-holding device which upon the releasing of same from the bolt will simultaneously arrange the parts so that the combination 30 may be readily changed.

With these and other objects in view the invention consists in the novel construction and combination of the several parts, as will be hereinafter more fully described, and particularly pointed out in the claims at the end 35 of the description.

In the accompanying drawings, like letters of reference are used to designate like parts in the several figures.

Figure 1 is a front elevation of the lock. Fig. 2 is an end elevation. Fig. 3 is a vertical section on the line III—III of Fig. 1, with the rear plate removed and showing the slide or plunger in elevation. Fig. 4 is a sectional plan on the line IV—IV of Fig. 1. Fig. 5 is a rear elevation of the lock with the bolt and retaining plate removed to expose the working parts. Fig. 6 is a vertical sectional view on the line VI—VI of Fig. 7 illustrating a

modification. Fig. 7 is a vertical sectional 50 longitudinal view of the form shown in Fig. 6 with a bolt or hasp in connection therewith, illustrating the parts in position for the withdrawal of the plunger for the removal of the hasp; and Fig. 8 is a vertical sectional fragmentary view on the line VIII—VIII of Fig. 7.

A designates a casing of any suitable construction having a removable plate *a* in the rear thereof and the plate *a'* arranged within the casing; the latter plate being either separate from the casing or formed integrally therewith.

At B, B are the combination or registering devices which are preferably located on opposite sides of the center of the casing and provided with the handles or knobs *b*, *b*, the said knobs each having a spindle *b'* extending within the casing in which the said spindles may revolve. Near the inner end of each spindle is a notched wheel *b*² rigidly secured to or formed integrally with said spindle. Surrounding the wheels *b*² are the rings *b*³ each having a single slot *b*⁴ adapted to register with the notches of the wheels *b*² by turning the knobs *b*, *b*, when the parts are in an 75 unlocked position, at which time the slot of the ring and one of the notches of the wheel is in position to receive a pin *b*⁵, so that both wheel and ring may rotate in unison to lock the parts together as will presently appear. 80 Surrounding the rings *b*³ and fitting into the casing is a suitably apertured plate *b*⁶ which apertures provide bearing surfaces for the peripheries of said rings when rotated as shown in Fig. 5. For retaining the working 85 parts within the casing I provide a removable apertured plate *b*⁷ in the apertures of which the inner ends of the spindle *b*, of the combination devices have a bearing.

C is the bolt or a similar locking device located between the removable plate *b*⁷ and the plate *a* of the casing between which said bolt is slidably held. The bolt is held fixed or removable by the engagement of the end of the stem *d* of the slide or plunger *D* engaging an 90 aperture *c* in said bolt. This plunger is preferably centrally located in the casing and between the oppositely arranged combination

devices B, B. The plunger is slidably held in the casing and is provided with outwardly extending bifurcated arms or projections d' arranged on opposite sides of the stem of the plunger and adapted to register with the slots in the rings b³ when forced inwardly to engage the bolt, and to pass through the same when the stem is withdrawn from the bolt. The arms d' have each a slot d² something larger than the thickness of the rings b³ so that when said slots register with the slotted rings, as shown in Fig. 4, the said rings may revolve through the slots of the arms to prevent the plunger from being withdrawn from the bolt. The arms d' of the plunger further serve to carry the pins b⁵ out of engagement with the notched wheels and rings when the same are brought into alignment with the slots d² of the arms d' for the purpose of withdrawing the plunger from the bolt to unlock the same and to change the combination if so desired, and to carry the pins to place the same in the slots of the rings b³ and notches of the wheels b² when the plunger is forced inwardly to engage the bolt as shown in full lines in Fig. 4. The plunger is further provided with a knob or handle d³ on the outer end of the stem d for the purpose of readily operating said plunger and disengaging same from the aperture c of the bolt. To allow for the movement of the plunger, the plates b⁷, b⁶ and a', of the casing have each a slot something larger than but formed similarly to the projecting arms d' of the plunger to permit said plunger to slide, as shown in dotted lines in Fig. 4, but which prevents any rotary movement of the plunger. At d⁴ is a slot in the front of the casing transversely arranged to the slots in which the plunger arms slide. This slot permits the plunger and arms to be readily inserted within the casing and yet prevents its withdrawal when turned at an angle to said slot.

On the peripheries of the knobs b of the combination devices are arranged figures or other characters agreeing in number to the number of notches on the wheels b². These characters are adapted to register with a suitable pointer or indicator, such for instance as is indicated by the line e on the casing, so that the combination may be set in any predetermined position by turning the knobs b. Other means, however, may be employed for this purpose if desired.

The parts being unlocked and the position of the knobs b being determined as described and a notch in each wheel b² brought into alignment with the slots of the rings b³ and arms d' of the plunger, it will be seen that by forcing the plunger inwardly from the unlocked position shown in dotted lines in Fig. 4 the end of the stem d will engage the aperture c of the bolt. This movement of the plunger places the pins b⁵, which are at this time carried by the bifurcated arms d' within the slots of the rings and in engagement with

the registering notches of the wheels b²; the slots d² of the arms also registering with said rings. By turning the knobs b the wheels b² and the rings b³ will rotate together by the action of the pin b⁵, as best shown in Fig. 5. At this time the parts are locked, as the solid parts of the rings b³ which pass through the slots of the arms d', of the plunger will rigidly hold the same in engagement with the bolt, and yet allow the ring and wheels to revolve. By bringing the pins b⁵ into alignment with the slots d² of the bifurcated arms, the plunger may be disengaged from the bolt and at the same time the pins b⁵ will be carried with the arms, as shown in dotted lines in Fig. 4. This will permit the notched wheels b² to be rotated independently of the ring b³, thereby allowing the combination to be changed, if desired, by simply turning the knobs b.

I have not illustrated nor described any means for moving the bolt C as it is obvious that any well-known means may be employed for this purpose.

I do not wish to confine myself to the exact construction shown for I may vary this in some instances without departing from the spirit of my invention.

The invention is not only applicable to locks having a sliding bolt, but to any form of lock in which the locking device may be engaged by a sliding plunger.

In Figs. 6, 7 and 8 I have shown how a single or a series of combinations may be arranged around a stem f; the said stem being passed through central apertures of a single or a series of rings f'. Slidably held in a slot in the stem f is a plunger f² having a series of slots corresponding to the number of combination devices arranged around the stem, each slot permitting the rotation of one of said combination devices when the same are in alignment with said slots. Each combination device has a ring f' provided with a slot f³ which is adapted to register with the internal grooves or notches f⁴ of the annular inclosing casing F, (there being as many casings as there are rings) each casing being preferably separated by a washer f⁶ from the next adjacent casing, the said washer being preferably secured to the stem f and provided with a slot for the passage of the plunger f². The casings F have letters or figures stamped or otherwise formed upon their peripheries corresponding in number to the slots f⁴ of said casings, so that the combinations may be changed or set when the figures are arranged in some predetermined position. These casings are rotatably held upon the rings f', but may rotate in unison therewith around the stem f when the pins f⁵ engage the notches of the casings F and the slots f³ of the rings f' as indicated in Fig. 6.

G is a hasp or other locking device having the enlarged ends g and g', the former hav-

ing a slot g^2 for the end of the plunger f^2 to engage while the latter is provided with a T-shaped slot g^3 . This slot is so shaped that when the plunger is pulled in the direction indicated by the arrow the smaller portion of the plunger will register with the narrow portion of the slot g^3 allowing the hasp to be removed, but when the plunger is in the position shown in Fig. 7, the enlarged portion g^4 of the plunger f^2 , will engage the enlarged portion of the slot g^3 at the same time that its end engages the slot in the end g of the hasp, thereby rigidly holding the hasp in a locked position. The operation of this form is similar to the operation of the form illustrated in the other views and differs mainly from them in the arrangement of the parts.

It will be seen that by forcing the plunger inwardly the end of the same will engage the locking device G arranged in the path of movement of said plunger. This movement of the plunger places the pins f^5 , which are carried by the notches of the plunger, within the slots of the rings and in engagement with the registering notches of the casings F ; the slots of the plunger also registering with said rings. By turning the casings F to some predetermined position the rings f' will rotate with the said casings by the action of the pins f^5 . At this time the solid parts of the rings f' which pass through the slots of the plunger will rigidly hold the same in engagement with the locking device, and yet will allow the casings and rings to revolve. By bringing the pins f^5 into alignment with the slots of the plunger, the same may be disengaged from the locking device, and at the same time the pins f^5 will be carried with the plunger to the spaces between the casings or in alignment with the washers when used, which separate said casings. This will permit the casings F to be rotated independently of the rings f' , thereby allowing the combination to be changed, if desired, by simply turning the casings.

I may arrange more than two combination devices around the plunger D , which would have a corresponding number of bifurcated arms; or I might arrange more than one set of notched wheels in each combination device if so desired.

Having thus fully described my invention, what I claim as new, and desire to secure by Letters Patent of the United States, is—

1. A combination lock having a locking device, a movable plunger arranged to engage said locking device, a combination device arranged around the plunger, a loose pin arranged to be carried by the combination device when the bolt is in a locked position and be carried by the plunger before the plunger can be disengaged from the locking device, substantially as described.

2. A lock of the character described having a locking device, a plunger arranged to engage the locking device, combination devices

arranged around the plunger, and means carried by the plunger for simultaneously arranging the parts so that the combination may be changed when the plunger is disengaged from the locking device, substantially as described.

3. A lock of the character described having a casing and a locking device, a plunger held within the casing arranged to allow or prevent movement of the locking device, combination devices surrounding the plunger and adapted to prevent any movement of said plunger except when in some predetermined position, and means operated by the plunger for permitting the combination to be changed, substantially as described.

4. A lock of the character described having a casing and a locking device within said casing, a plunger held within the casing and engaging said locking device, a combination device comprising a notched wheel and a ring having a slot therein located within said casing, the said ring adapted to rotate separately or in unison with the notched wheel to set or alter the combination, and means carried by the plunger for simultaneously arranging the parts to change said combination when the plunger is disengaged from the locking device, substantially as described.

5. A combination lock having a casing and a locking device arranged within said casing, a plunger arranged to engage the locking device and having outwardly projecting bifurcated arms on the stem of the plunger, and means located within the casing for engaging said arms to prevent the plunger from being disengaged from the locking device, substantially as described.

6. A lock of the character described having a casing and a locking bolt arranged to slide in said casing, a plunger slidably held within the casing and engaging a portion of the locking bolt, the said plunger having outwardly extending bifurcated arms located on the stem of the plunger and adapted to move with same, a slotted ring arranged in the path of movement of the arms of the plunger, and a notched wheel rotatably held within the slotted ring, and means for rotating both ring and notched wheel in unison, the said slotted ring adapted to prevent or allow the bolt to be released from the plunger, substantially as described.

7. A lock of the character described having a casing and a locking bolt arranged to slide in said casing, a plunger slidably held within the casing adapted to engage an aperture in said locking bolt, the said plunger having outwardly extending bifurcated arms located on the stem of the plunger, slotted rings located on opposite sides of the plunger and arranged in the path of movement of the arms of said plunger, a notched wheel rotatably held within each slotted ring, a pin adapted to be carried by each arm of the plunger and be placed by same in alignment

with the slot in the ring and a notch of the wheel, and means for rotating said wheel and ring, substantially as described.

8. A lock of the character described having a casing and a locking device within said casing, a plunger slidably held within the casing, and adapted to engage the locking device, combination devices located within the casing and arranged around the plunger, a removable plate arranged to retain the com-

bination devices within the casing and means for actuating said combinations, substantially as described.

In testimony whereof I affix my signature in presence of two witnesses.

BENJAMIN BUNDY.
